ATTORNEY

UNITED STATES PATENT OFFICE.

HENRY SANTULLI, OF BROOKLYN, NEW YORK.

TORPEDO GUARD OR SHIELD.

1,367,566.

Specification of Letters Patent.

Patented Feb. 8, 1921.

Application filed July 16, 1919. Serial No. 311,151.

To all whom it may concern:

Be it known that I, HENRY SANTULLI, a citizen of the United States, and resident of the borough of Brooklyn, county of Kings, and city and State of New York, have invented certain new and useful Improvements in Torpedo Guards or Shields, of which the following is a specification.

The device has for its purpose the protection of the ship against shelling and for that purpose, the outstanding barriers are arranged and constructed in such a manner as to receive the shells and allow them to explode at a distance from the ship sufficiently great to make them ineffective as destructive agents.

A further object of the invention is to provide a means of the character described and for the purposes set forth which means can be readily repaired should it be damaged.

The construction and operation of my device will be fully set forth as the specification progresses.

The following is what I consider a good means of carrying out my invention and the accompanying drawing should be referred to for a complete understanding of the specification which follows:—

In the drawings:—

Figure 1, shows in side elevation the diagram of a ship upon which my guard is secured.

Fig. 2, is a top plan view of the guard.

Fig. 3, a sectional view of the guard and the side of the ship to which it is attached.

Fig. 4, a small detail of an elevation, this detail is an end elevation.

Fig. 5, shows a detail in side elevation.

Similar reference numerals indicate like parts in all of the figures where they appear.

The ship to which my device is attached may be of any ordinary construction, shape or size, and as it is not necessary to modify the construction of the ship, I will indicate by the reference character 1 the ship shown in diagram in Fig. 1, allowing the character 1 to indicate the whole ship.

Arranged adjacent to the sides of the ship are plates 2 extending the full length of the sides and although in the drawing I have illustrated only one plate and the parts supporting it and adjacent thereto, it will be understood that all of the parts described are duplicated at the other side of the ship.

The plate 2 which may be of armor or

other suitable material extends the full length of the ship and projects slightly beyond each end thereof, and this plate 2 may be made up of a series of sections secured together in such a manner as to produce one integral unit.

The lower end of the plate 2 is secured to the ship by the means of a hinged block 3 and I provide a series of these blocks probably spaced 10 or 20 feet apart.

The plate 2 extends downward from the ship at an angle and this angle may be determined by the conditions or requirements. Probably a plate arranged at an angle of approximately 50 degrees will be found most serviceable.

High up on the plate and spaced apart are a plurality of guides 4 and engaged in or upon these guides is a plunger 5. A cylinder 6 which may extend through the side of the ship 1 contains a spring 7 and at the inner end of the cylinder 6, I provide an air outlet 8 controlled by a valve 9. When the plate 2 is moved inward its movement will be controlled by the spring 7 and by the discharge of air past the valve 9. The spring 7 may be relatively weak, intended merely to urge the plunger 5 outward. The discharge of air may from time to time be regulated so that the pressure required to move the plate 2 backward may be approximately the same regardless of the resistance to this movement which may result from corrosion or from the fouling of the parts.

Supported upon the plate 2 are a plurality of guides and these guides are shown in end elevation at 10, 11, 12, 13 and 14 in Fig. 2. And between each pair of guides is a movable plate indicated at 15, 16, 17, 18, 19 and 20 in Fig. 2.

These plates 15 to 20 inclusive, are movable vertically in their respective guides, and I may provide flexible members 21—21 connecting each plate and its next adjacent plate for a purpose that shall appear later.

A series of rollers 22—22 arranged upon the top of the plate receive the flexible members 21—21 and as these flexible members are engaged to adjacent plates, the operation will be as follows. When the plate 17 is moved downward the plates 16 and 18 will be elevated and when the force which causes the plate 17 to move downward is no longer effective, the plates 16 and 18 will return the plate 17 to its normal conditions.

In Fig. 4, I show a back plate 23 pro-

vided with a channel 24. This back plate 23 is similar to the plate 2 though provided with a plurality of channels 24. One channel is at about midwidth of the movable plates. 5 The smaller detail in Fig. 5 shows this construction and in this detail, a small portion of the plate 23 is shown having two channels 24 and 25, and only two movable plates 26 and 27 are indicated in this detail. These 10 plates are connected by a flexible member 28 passing over the rollers 29 and 30 and it is my intention in this construction that the plates along the side of the boat should be similarly connected in pairs, each one of a 15 pair serving as a balancing or returning member for the other plate of the pair.

From the foregoing description, it is thought that the operation of my device will be fully understood. However, I will briefly 20 describe the operation referring to the parts generally by their reference characters.

A boat equipped with my completed device which consists of a pair of plates 2, one arranged at each side of the boat and all of 25 the other parts supported and adjacent thereto, is the subject of attack by submarine or other enemy craft, and a torpedo discharged at this boat will strike one of the plates arranged along the side and the force 30 of the impact of the torpedo will be lessened, at the same time the angular arrangement of the entire guard will cause the plate which receives the blow to move downward and when the force of the blow has been spent, 35 the plate struck will again return to its normal position.

It will be noted that the exposed surface of the guides 10 to 14 inclusive are tapered. This will tend to deflect a torpedo from the stationary portion of my device.

40

The plate 2 or the guard proper may be made in a series of sections if desired as indicated by the lines 31 and 32, but I prefer the whole as shown and described.

Having carefully and fully described my 45 invention, what I claim and desire to secure by Letters Patent is:—

1. A torpedo guard having a pivoted plate and a plurality of vertically movable plates thereon, the alternate plates being connected 50 together to move oppositely in unison.

2. A torpedo guard having a plate hingedly connected to the side of a ship and a plurality of vertically movable plates thereon, guides for said plates and means 55 for returning said vertically movable plates to normal position after each movement.

3. A torpedo guard consisting of a plate extending along the side of a ship, a plurality of hinges securing said plate to said ship, a plurality of pistons and cylinders between said plate and said ship and adapted to yieldingly resist the movement of said plate toward the side of the ship, a plurality of guides upon said plate and a plurality of 60 movable plates in said guides and flexible means connecting said plates for retaining said plates in said guides.

Signed at New York city in the county and State of New York, this 20 day of June 70 1919.

HENRY SANTULLI.
